Primary Examiner—Lucy Lieberman

(57) **CLAIM**

The ornamental design for a combined watch and portion of a watchband, as shown and described.

DESCRIPTION

FIG. 1 is a front elevation of a combined watch and portion of a watchband showing our new design;

FIG. 2 is a rear elevation thereof;

FIG. 3 is a left side elevation thereof;

FIG. 4 is a right side elevation thereof;

FIG. 5 is a front and right side perspective view thereof; and,

FIG. 6 is a bottom view thereof.

The broken lines in the drawings are used to illustrate portions of the watch and watchband that do not form part of the claimed design.
